CONCRETE SCREED AND GUIDE

Gordon M. Tamblyn, Denver, Colo.

Application June 17, 1941, Serial No. 398,381

5 Claims. (Cl. 72—128)

This invention relates to a device for leveling and finishing relatively large concrete areas, such as floors, platforms, sidewalks, roadways, and the like. Such surfaces are finished by a surfacing device known as a screed and the principal object of this invention is to provide a highly efficient screed construction and highly efficient means for supporting and guiding the screed on the various types of construction which may be encountered by a builder.

Other objects of the invention are to provide a screed runway which will not be affected by moisture, sand, cement, weather conditions, etc.; to provide supporting means for the runway by means of which the latter can be quickly and easily brought to the desired height and to a perfect level; and to provide screed runway supporting means which can be adapted to concrete forms, structural members and other supporting structures.

Other objects and advantages reside in the detail construction of the invention, which is designed for simplicity, economy, and efficiency. These will become more apparent from the following description.

In the following detailed description of the invention reference is had to the accompanying drawings which form a part hereof. Like numerals refer to like parts in all views of the drawings and throughout the description.

In the drawings:

Fig. 1 is a plan view of the improved screed and its supporting structure as it would appear in use;

Fig. 2 is a longitudinal section, taken on the line 2—2, Fig. 1, illustrating a side view of the runway support or screed leg;

Fig. 3 is a cross section, taken on the line 3—3, Fig. 1, illustrating a side view of the improved screed;

Fig. 4 is an enlarged cross section through the screed;

Fig. 5 is an enlarged detail side view of one form of screed leg used for supporting the screed runway;

Fig. 6 is a vertical section therethrough, taken on the line 6—6, Fig. 5;

Fig. 7 is a front view of the screed leg as it would appear when arranged for clamping a structural member;

Fig. 8 is a vertical section therethrough, taken on the line 8—8, Fig. 7;

Fig. 9 is a detail top view of the clamping member employed in Figs. 7 and 8;

Fig. 10 is a detail view illustrating an alternate

leveling head which may be used on the screed leg;

Fig. 11 is a side view of the screed carriage;

Fig. 12 is a horizontal cross section therethrough, taken on the line 12—12, Fig. 11;

Fig. 13 illustrates the improved screed runway in use supporting a vibrating machine on a roadway;

Fig. 14 is a cross sectional view, taken on the line 14—14, Fig. 13;

Fig. 15 is a similar view, taken on the line 15—15, Fig. 13;

Fig. 16 illustrates a type of screed leg for use on the ground;

Fig. 17 is a vertical section through the leg of Fig. 16;

Fig. 18 illustrates an alternate form of leg; and

Fig. 19 is a vertical section through the alternate form, taken on the line 19—19, Fig. 18.

In Fig. 1, a typical floor form for supporting the concrete of a concrete floor is indicated at 13 with the reinforcing bars in place thereon at 14. The concrete being poured is indicated at 15.

The improved screed is supported on longitudinally extending tubular members or runways 16 formed of pipe or metal tubing. The tubular members are supported from the floor form 13 by means of screed legs. The preferred form of screed leg comprises a head 17 provided at its top with a horizontally extending, cylindrical socket 18 through which the tubular members 16 can be passed. The heads terminate below the upper surface of the tubular member when the latter are in place in the heads. A threaded socket 19 is formed in the bottom of each head to receive the upper extremity of a threaded supporting pipe 20.

A clamp bolt 21 extends downwardly through the head, the head of the bolt resting on a shoulder 22 in the screed head. When the screed leg is in place, the pipe 20 rests on the forms 13 and the bolt 21 extends through the forms to receive a clamp nut 23 by means of which the entire leg is clamped to the form. The height of the screed leg is adjusted by loosening the nut 23 and rotating the pipe 20 to the right or left so that the tubular member 16 can be brought to a perfect level.

In some instances, it is necessary to clamp the screed leg to a steel column, beam or other structural member. For such occasions, a clamping plate 24 is provided which is clamped to the bottom of the head 17 by means of the clamp bolt

21. The clamp bolt is held in an axial position by means of a plug 25 which is screwed into the socket 19 after the pipe 20 has been removed. It is preferred to have a square hole in this plug for the insertion of a plug wrench.

The clamp plate 24 is held in place and prevented from rotation by means of an upwardly extending lug 26 which enters into any desired one of a plurality of receiving sockets 27 formed in the head 17, depending on the position of the structural member. It can be readily seen that by simply tightening the nut 23, the clamp plate can be caused to engage the edge of a structural member, such as indicated at 28, to hold the screed leg in place thereon.

An alternate form of screed leg is illustrated in Fig. 10 which provides very accurate and quick aligning adjustment. This form consists of a coupling member 29 threaded at its bottom to receive a threaded supporting pipe 30 and threaded at its top, in an opposite direction, to receive the lower leg of an adjusting screw 31. The upper leg of the adjusting screw 31 is threaded in a direction opposite to the lower leg and is received in a threaded socket 32 in a screed head 33.

The screed head 33 is provided with an arcuate notch in its top for receiving the tubular runway member 16 as in the preceding form. The adjusting screw 31 is formed with a knurled flange member 34 by means of which it may be readily rotated in either direction. It can be seen that, when rotated in one direction, it will separate the coupling 29 and the head 33 and, when rotated in the other direction, it will draw these members together so as to provide ready means for leveling the screed runways.

The screed comprises a cross bar 35 to which a leveling beam 36 is attached by means of downwardly depending beam arms 37. The beam arms extend oppositely outward at their bottoms to engage opposite sides of the beam 36 and the latter is secured therein by means of suitable clamp bolts 38. The clamp bolts 38 pass through slotted openings 39 in the arms 37 so that the leveling beam may be accurately adjusted to a position parallel to the cross bar 35. The bottom face of the leveling beam is covered with a sheet metal facing 40 for contacting the concrete.

Two leveling beams are provided, one presenting a flat bottom with relatively sharp rectangular edges, as indicated at 41 in Fig. 4, and one presenting a rounded bottom as illustrated in solid line in Fig. 4. The flat bottomed beam is preferable for leveling the rough concrete while the rounded form is preferable for smoothing the finish cement coating.

The cross bar is sufficiently long to extend completely over the two tubular runways 16. The leveling beam is shorter so that it may be passed downwardly between the runways. The cross bar may be slid directly on the runways if desired. It is preferred, however, to employ suitable carriages on the runways to hold the cross bar in a perpendicular direction.

These carriages comprise inverted trough-like slide members 42 which ride on and slide along the tubular runways 16. A suitable handle 43 is provided to facilitate moving them. A vertical post 44 arises from each slide member 42 and a sleeve 45 is mounted on each post. These sleeves are provided with downwardly opening yokes 46 which fit over the cross bar 35 so as to

5 maintain its constantly perpendicular with the axis of the runways 16. The slides 42 are cut away at their mid-portions, as shown at 47, so that they may be placed directly over the screed legs when desired.

It can be readily seen that the operator or operators can grasp the handles 43 and pull the screed back and forth over the concrete or the finish, bringing the latter to a perfect level determined by the level of the tubular runways 16. The screed can also be swung back and forth by pushing one side forward and the other rearward so as to give a rotating effect, since the sleeves 45 are free to rotate on the post 44.

15 It will be noted that there are no obstructions on the leg pipes so that they may be easily withdrawn and the small holes remaining can be easily cemented up.

In Figs. 16 and 17 an alternate form of leg is 20 illustrated for use in laying walks, roadways, platforms, etc. on the ground. In this form a pointed spear-head 48 is employed which is designed to be driven into the ground. The spear-head is cast with longitudinally extending fins 25 49 which act to guide it vertically into the ground. An axial socket 50 is formed in the top of the spear-head to receive a pipe support 51. The upper extremity of the pipe 51 is threaded into a head 52 which may be any of the previously described heads, as desired.

The head 52 is formed with a clamping jaw 53 which closes one side of a runway channel 54 in its top. The clamping jaw is held in place by means of a clamp screw 55. By simply loosening the screws 55 the runways can be quickly and easily lifted from place.

With this form of screed leg the spear-heads are simply driven into the ground along the runway lines, the pipes with their heads in place are inserted into the spear-heads, and the runways are placed in the channels 54 and clamped in place by means of the screws 55.

Another alternate form of leg is illustrated in Figs. 18 and 19. This form can receive any 45 of the previously described heads upon the upper extremity of a pipe nipple 56, the lower extremity of which has left-handed threads 57 which are threaded into a coupling block 58. The coupling block is universal in its application. 50 It can be placed on a pipe leg such as those illustrated at 20 and 51. The bolt 21 of Fig. 6 can be inserted through it, a socket 59 being provided for the bolt head or the clamp plate 24 of Fig. 8 can be attached thereto, since a notch 55 60 is provided for the lug 26. Height adjustment can be made by simply rotating the nipple 56.

In Figs. 13, 14, and 15 a tamping device is illustrated for use on the improved runways. This 60 device comprises a pair of parallel cross members 61 resting at their extremities on the runways. The cross members are held in fixed parallel relation by means of end plates 62, welded or otherwise secured thereto. Handles 63 arise from the end plates by means of which the entire assembly may be slid along the runways. A motor platform 64 rests on the cross members to carry a motor 65 having an eccentric rotary counterweight 66.

A plurality of horizontal tamping bars 67 are suspended below the cross members 61 on adjustable jack screws 68 by means of which the tamping bars can be brought to a perfect level.

The operation of the tamping device is clearly apparent. The operation of the motor, due to

the eccentric counterweight, vibrates the tamping bars in the concrete as the device is drawn along the runways so as to settle, spread, and compact the concrete.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. Means for supporting a runway for a concrete finishing device comprising: a head member; a horizontally extending recess in the upper extremity of said head member for receiving said runway; a threaded socket in the lower extremity of said head member at right angles to the axis of said recess; a tubular leg threaded into said threaded socket for supporting said head; a bolt extending through said head and through said leg; and means on said bolt for clamping said leg against a supporting structure.

2. Means for supporting a runway for a concrete finishing device comprising: a head member; a horizontally extending recess in the upper extremity of said head member for receiving said runway; a threaded socket in the lower extremity of said head member at right angles to the axis of said recess; a clamping jaw forming one side of said recess; means for drawing said clamping jaw toward said recess to restrict the latter; a tubular leg threaded into said threaded

socket for supporting said head above a surface; and a bolt extending downwardly through said head member and said leg for clamping the latter into a surface.

5 3. A screed leg for supporting a pipe-like screed runway comprising: a head member; a receiving notch in the upper extremity of said head member to receive said runway; clamping means for clamping said runway in said notch; a pipe nipple threaded into the bottom of said head member; the opposite ends of said nipple being threaded in opposite directions; a coupling block threaded on the lower extremity of said nipple; and means for securing said block to a supporting surface.

10 4. A screed support comprising: a head member having a groove for receiving a screed; a tubular leg inserted into the bottom of said head for supporting said head above a supporting surface; a bolt extending downwardly through said head and through said tubular leg; and means on the extremity of said bolt for clamping said tubular leg to said supporting surface.

15 5. A screed support comprising: a head member having a groove for receiving a screed; a tubular leg inserted into the bottom of said head for supporting said head above a supporting surface; a bolt extending downwardly through said head and through said tubular leg; and means on the extremity of said bolt for clamping said tubular leg to said supporting surface, said tubular leg being threaded into said head so that the projecting length of said leg may be varied.

GORDON M. TAMELYN.
